UNITED STATES PATENT OFFICE

JOSEPH MARSHALL, OF NOTTINGHAM, ENGLAND, ASSIGNOR TO BOOT'S PURE DRUG COMPANY LIMITED, OF NOTTINGHAM, ENGLAND, A COMPANY OF GREAT BRITAIN

AMYL-CRESOLS AND PROCESS FOR MAKING

No Drawing. Application filed December 20, 1929, Serial No. 415,618, and in Great Britain March 26, 1929.

This invention relates to the production of monohydric phenols and aims at producing bodies possessing a very high phenol coefficient and having a toxic action of such a low order that they are of great value as therapeutic substances with considerable antiseptic and disinfectant properties.

It has been recognized that the introduction of a methyl group into the molecule of phenol increases its antiseptic power. It has now been discovered, however, that if meta-cresyl n-valerate be converted into n-valeryl cresol, the ketone produced may be reduced to a methyl n-amyl phenol possessing a phenol coefficient of about 280 and with a toxicity which is very low when compared with that of phenol or the cresols, and, as a matter of fact, it is also found that other normal amyl cresols have a phenol coefficient which is very large in comparison with that of known phenols or other cresols. Thus, the phenol coefficient of 6-n-amyl-o-cresol

is 250, and that of 4-n-amyl-o-cresol

is 300, and that of 2-n-amyl-p-cresol

is 250.

It will be appreciated that even if it had been known that a normal amyl group could, by the method herein described, be introduced into the nucleus of a cresol, it could not be foreseen that the introduction of that radicle would so considerably increase the antiseptic power, and certainly it could not be foreseen that the introduction of the said group into a particular position in meta-cresol would result in the production of a body with a phenol coefficient of 280.

Thus according to the present invention, a cresyl n-valerate is converted into a normal amyl cresol by subjecting the ester to the action of aluminum chloride for a short time and reducing the products. It is found most convenient to employ rather more than one molecular quantity of anhydrous aluminum chloride. As a result of the action of aluminum chloride, the n-valeryl group is caused to move and in the case of m-cresyl n-valerate,

it takes up a position which is ortho to the hydroxyl group and para to the methyl group. This reaction is shown by the following equation:

In the case of o-cresyl n-valerate a mixture of two ketones is produced, in one of which the valeryl group is ortho to the hydroxyl group and in the other, para to the hydroxyl group. In each case the ketone so formed, and also n-valeryl-p-cresol (in which the n-valeryl group is ortho to the hydroxyl group) is reduced to a n-amyl cresol in which the n-amyl group occupies the same position as the original n-valeryl group. In the case of the production of n-amyl meta cresol the reduction may be represented as follows:

The resultant n-amyl cresols, as already mentioned, possess very high phenol coefficients, viz., between 250 and 300.

In order that the invention may be clearly understood and readily carried into effect, some practical methods of carrying out the process according to the invention will now be described in somewhat greater detail by way of example.

Example 1

In the production of 6-n-amyl-m-cresol ($\text{OH}:\text{CH}_3:\text{C}_5\text{H}_{11}=1:3:6$), equal parts by weight of meta-cresol n-valerate and aluminum chloride are mixed and heated quickly to 160° C. , which temperature is maintained for one and a half hours, the mixture being stirred and shaken occasionally at the beginning of the operation. After cooling, dilute

95

90

100

hydrochloric acid is added and steam is blown through the mixture. After cooling, an oil separates and this is distilled in vacuum. Practically the whole of the material boils at about 152 to 154° C. under 15 mm. pressure. It may be purified by cooling in a freezing mixture and separating a small quantity of oily material, and the crystals melt at about 60° C. 120 parts of this ketone, which is n-valeryl-meta-cresol, are mixed with 400 parts by weight of zinc amalgam, and boiled under a reflux condenser with a sufficient quantity of a mixture of equal parts by weight of water, alcohol, and concentrated hydrochloric acid. The addition of the alcohol materially influences the time taken for the ketone to be completely reduced. When this reduction is complete, steam is blown through the mixture to remove the alcohol, which may be recovered for use in a subsequent batch, and then the reduction mixture is allowed to cool and the 6-n-amyl-meta-cresol is extracted with ether and purified by fractional distillation. It boils at 137 to 139° C. under 15 mm. pressure. It may be purified by recrystallization from petrol ether, using a freezing mixture, and separating the crystals by filtering at a low temperature so as to separate a small quantity of oily material. The product so obtained melts at about 24 to 25° C. and possesses a phenol coefficient of about 280.

Example 2

35 In producing n-amyl-o-cresols, equal parts by weight of o-cresyl n-valerate and aluminum chloride are mixed and heated quickly to 160 to 170° C., which temperature is maintained for one and a half hours, the mixture being stirred occasionally at the beginning of the operation. After cooling, the mass is heated with dilute hydrochloric acid on a steam bath or by blowing steam into it until the practically solid mass has been converted into a mobile oil which is separated from the dilute hydrochloric acid and distilled in vacuo. Two main fractions are collected, the first at about 140 to 150°, which is chiefly 6-n-valeryl-o-cresol

50 $(OH:CH_3:CO.C_4H_9=1:2:6)$,

and the second fraction at about 200° to 205°. The lower fraction solidifies on cooling in a freezing mixture and it may be freed at a low 55 temperature from adherent oil by draining on a filter pump. This ketone, when pure, melts at about 18°.

The higher fraction may be purified by recrystallization from benzene or other suitable solvent, and this ketone, which is 4-n-valeryl-o-cresol

$(OH:CH_3:CO.C_4H_9=1:2:4)$,

is thus obtained as colourless prisms which 65 have a melting point of about 103 to 104°.

Each of these ketones is then separately boiled under a reflux condenser with about 3½ times its weight of amalgamated zinc and a sufficient quantity of the acid mixture as described in Example 1. The reduced products may be separated and purified as described in Example 1, and when pure, the 6-n-amyl-o-cresol thus produced has a melting point of about 32° and a phenol coefficient of about 250, whilst the 4-n-amyl-o-cresol has a melting point of about 29° C. and its phenol coefficient is in the neighborhood of 300.

Example 3

In order to produce 2-n-amyl-p-cresol ($OH:CH_3:CO.C_4H_9=1:4:2$), the 2-n-valeryl-p-cresol made by the known methods is boiled under a reflux condenser with 3½ times its weight of amalgamated zinc and a sufficient quantity of the alcoholic acid mixture described in Example 1, and when reduction is complete, the amyl p-cresol may be separated from the reduction mixture by any convenient process, such as that described in Example 1, and it may be purified by distillation under reduced pressure and by crystallization at a low temperature. When pure, 2-n-amyl-p-cresol has a phenol coefficient of about 250, and a melting point of 10°.

I claim:—

1. The process for the production of a normal amyl cresol which consists in effecting a reaction between a cresyl n-valerate and aluminum chloride and reducing the resulting ketone.

2. The process for the production of a normal amyl cresol which consists in effecting a reaction between a cresyl n-valerate and a small excess over a molecular proportion of aluminum chloride and reducing the resulting ketone.

3. The process for the production of a normal amyl cresol which consists in reducing a normal valeryl cresol by means of amalgamated zinc and hydrochloric acid.

4. The process for the production of a normal amyl cresol which consists in effecting a reaction between a cresyl n-valerate and aluminum chloride and reducing the resulting ketone by means of amalgamated zinc and hydrochloric acid.

5. The process for the production of a normal amyl derivative of a phenol which consists in effecting a reaction between meta-cresyl valerate and aluminum chloride and reducing the resulting ketone.

6. The process for the production of a normal amyl derivative of a phenol which consists in effecting a reaction between meta-cresyl valerate and aluminum chloride and reducing the resulting ketone by means of amalgamated zinc and hydrochloric acid.

7. The process for the production of a normal amyl derivative of a phenol which

consists in reducing valeryl meta-cresol by means of amalgamated zinc and hydrochloric acid.

8. The process for the production of 6-n-
5 amyl-m-cresol ($\text{OH}:\text{CH}_3:\text{C}_5\text{H}_{11}=1:3:6$)
which consists in effecting a reaction between
meta-cresol n-valerate and aluminum chlo-
ride and reducing the resulting normal-
valeryl-meta-cresol by means of amalga-
mated zinc and hydrochloric acid.

10 9. The process for the production of 6-n-
amyl-m-cresol ($\text{OH}:\text{CH}_3:\text{C}_5\text{H}_{11}=1:3:6$)
which consists in mixing equal parts by
weight of meta-cresol n-valerate and alum-
15 inum chloride, heating the mixture until the
reaction is completed and reducing the re-
sulting normal-valeryl-meta-cresol by mix-
ing with zinc amalgam and boiling with a
mixture of equal parts by weight of water,
20 alcohol and concentrated hydrochloric acid.

10 10. A therapeutic substance comprising a
normal amyl cresol, said substance having a
phenol coefficient between 250 and 300.

11. A therapeutic substance comprising a
normal amyl meta cresol, said substance hav-
ing a phenol coefficient of about 280.

12. A therapeutic substance comprising 6-
n-amyl-m-cresol ($\text{OH}:\text{CH}_3:\text{C}_5\text{H}_{11}=1:3:6$),
said substance having, in the pure condition,
a phenol coefficient of about 280.

13. The process for the production of
normal amyl ortho cresols which consists in
effecting a reaction between ortho cresyl n-
valerate and aluminum chloride, separating
35 the ketones formed and reducing said ketones
separately by means of amalgamated zinc
and hydrochloric acid.

14. The process for the production of a
normal amyl para-cresol which consists in
40 reducing a normal valeryl para-cresol by
means of amalgamated zinc and hydrochloric
acid.

15. A therapeutic substance comprising a
normal amyl ortho-cresol, said substance
45 having a phenol co-efficient of between about
250 and 300.

16. A therapeutic substance comprising 2-
n-amyl-para-cresol

($\text{OH}:\text{CH}_3:\text{C}_5\text{H}_{11}=1:4:2$),

50 said substance having, in the pure condition,
a phenol co-efficient of about 250.

In witness whereof I hereunto subscribe
my name this 6th day of December, 1929.

55 JOSEPH MARSHALL.
